EYEGGLASS LENS GRINDING APPARATUS

Leopold H. Metzger and Wilson B. Muse, Chicago,
Ill., assignors, by mesne assignments, to Super-
Cut, Inc., Chicago, Ill., a corporation of Illinois

Application May 1, 1946, Serial No. 666,314

11 Claims. (Cl. 51—134.5)

1

The present invention relates generally to apparatus for use in grinding eyeglass lenses. More particularly the invention relates to that type of eyeglass lens grinding apparatus which as its principal components or parts comprises (1) a base structure which carries an electric motor and is supported in an elevated position by way of a table, bench or other support; (2) a vertically extending spindle which is mounted by way of anti-friction bearings on the base structure to rotate about its axis, has a driving connection between it and the armature of the motor whereby it is driven in connection with operation of the motor, and embodies an upwardly tapered upper end; and (3) a rigid horizontally disposed wheel which embodies in the hub portion thereof an upwardly tapered open bottom socket whereby it may be mounted removably on, and connected for friction drive by, the upwardly tapered upper end of the spindle, has the upper end surface thereof curved and provided with abrasive particles, and is adapted while being driven by the spindle in connection with a lens grinding operation to have a lens blank pressed against its upper end surface in order that the blank is ground by the abrasive particles to a curvature corresponding to that of the upper surface of the wheel.

In grinding a lens blank with an apparatus of the aforementioned type the blank is first rough ground by way of a wheel having coarse abrasive particles, is then ground by way of a grinding wheel having finer abrasive particles, and is then provided with a so-called "finish" grind by way of a wheel having still finer abrasive particles. In order to subject the lens blank to the three separate and independent grinding operations it is necessary successively to mount the grinding wheels on the power driven spindle. This requires for each successive grinding operation stopping the apparatus and then removing one grinding wheel and replacing such wheel with another grinding wheel. In practice it has been found that time is consumed and difficulty is encountered in removing a grinding wheel preparatory to replacement thereof by another wheel due to the fact that the friction drive between the wheel and spindle is generally so tight or secure that it is necessary in connection with a wheel removing operation to stop the apparatus and then break the friction drive between the wheel and the spindle by tapping the wheel in an upward direction by a hammer or like tool.

The primary object of the invention is to provide an eyeglass lens grinding apparatus which is an improvement upon, and eliminates the dis-

2

advantages and defections of, conventional apparatus by reason of the fact that it embodies as a part thereof a simple and novel device whereby at the end of any lens blank grinding operation the grinding wheel on the upwardly tapered upper end of the power driven spindle may be quickly and readily raised a slight distance with respect to the spindle in order to break the friction drive between the wheel and the spindle and thus release the wheel so that it may be removed from the spindle without the use of a hammer or similar tool.

Another object of the invention is to provide an eyeglass lens grinding apparatus of the last mentioned character in which the device for separating or raising the grinding wheel with respect to the spindle at the conclusion of a grinding operation and preparatory to replacement of the wheel by another wheel for further grinding of the lens blank being ground, comprises a lever which is mounted for vertical swinging movement and has at one end thereof means operative in response to swinging movement of the lever in one direction to engage the grinding wheel with sufficient pressure to break the friction drive and raise the wheel a comparatively small distance with respect to the spindle.

Another object of the invention is to provide an eyeglass lens grinding apparatus of the type and character under consideration in which the lever of the wheel removing device has limited vertical swinging movement in both directions and the wheel engaging and raising means of the device is adjustable in order to control or selectively determine or vary the amount of raising of the wheel with respect to the spindle when the lever is swung to its full extent in the proper direction for effecting removal of the wheel.

Another object of the invention is to provide an eyeglass lens grinding apparatus of the last mentioned type and character in which the lever of the device is in the form of a foot actuated treadle and the wheel engaging and raising means of the device embodies a rod which extends through a longitudinal bore in the power driven spindle of the apparatus and is adapted when shifted upwards in response to proper swinging of the lever to engage and act on the central upper portion of the grinding wheel on the spindle.

A further object of the invention is to provide an eyeglass lens grinding apparatus in which the device for facilitating removal of the grinding wheel from the spindle has associated therewith a brake means whereby when the device is actu-

ated for wheel removing purposes the spindle is automatically brought quickly to rest.

A still further object of the invention is to provide an eyeglass lens grinding apparatus which is generally of new and improved construction, effectively and efficiently fulfills its intended purpose and is characterized by the fact that it may be operated expeditiously and with facility.

Other objects of the invention and the various advantages and characteristics of the present eyeglass lens grinding apparatus will be apparent from a consideration of the following detailed description.

The invention consists in the several novel features which are hereinafter set forth and are more particularly defined by claims at the conclusion hereof.

In the drawings which accompany and form a part of this specification or disclosure and in which like numérais of reference denote corresponding parts throughout the several views:

Figure 1 is a vertical longitudinal section of an eyeglass lens grinding apparatus embodying the invention;

Figure 2 is a fragmentary front view illustrating in detail the construction and design of the device for raising the grinding wheel with respect to the spindle in order to break the friction drive between the wheel and the spindle preparatory to removal of the wheel for purposes of replacement or substitution; and

Figure 3 is an enlarged section taken on the line 3—3 of Figure 1 and showing the manner in which the rod of the wheel removing device extends through the longitudinal bore in the spindle of the apparatus and serves in connection with upward shift thereof to raise the wheel a slight distance with respect to the spindle and also showing the manner in which the brake means that is associated with the wheel removing device operates in connection with actuation of the device to brake the spindle.

The apparatus which is shown in the drawings constitutes the preferred form or embodiment of the invention. It is essentially designed for grinding to a predetermined curvature an eyeglass lens blank 5 and as its principal parts comprises a base structure 6, a bowl shaped receptacle 7, a vertically extending spindle 8, a grinding wheel 9, a pressure exerting arm 10 and a device 11 for use in effecting removal of the grinding wheel 9 when it is desired to substitute another wheel for it in connection with a lens blank grinding operation.

The base structure 6 is positioned or mounted on a table 12 in order that it is supported at a suitable height above the floor on which the table rests. It is horizontally elongated and embodies a horizontal top wall 13 and a continuous depending side wall 14. The top wall 13 defines with the depending side wall 14 an open bottom compartment 15 and has at one end thereof an integral upstanding annular flange 16, the upper margin of which is shaped to form a seat 17.

The receptacle 7 surrounds and serves as a shield for the grinding wheel 9 during a lens blank grinding operation and consists of a circular bottom wall and a cylindrical side wall which is connected to and extends upwards from the outer marginal portion of the bottom wall. Such marginal portion of the bottom wall of the receptacle rests on, and is shaped conformably to, the seat 17 on the upper margin of the annular

flange 16. As shown in Figure 1 of the drawings the bottom wall of the receptacle 7 has a centrally disposed circular aperture 18. The receptacle is removable from the base structure 6 in order that it may be cleaned.

The vertically extending spindle has the central portion thereof journalled in anti-friction bearings 19 on the top wall 13 of the base structure 6 and is arranged so that the lower end thereof projects into the compartment 15 and its upper end projects upwards through the circular aperture 18 into the central lower portion of the interior of the receptacle 7. As shown in Figure 3 the bearings 19 are so arranged and designed that they not only support the spindle for rotation about its axis but also hold the spindle against axial displacement relatively to the top wall 13 of the base structure 6. An electric motor 20 serves to drive the spindle 8 through the medium of a belt and pulley connection 21. Such motor is mounted on the end of the top wall 13 that is opposite the upstanding annular flange 16, and is arranged so that the armature shaft thereof extends vertically. A conventional switch (not shown) serves to control the motor. It is contemplated that after each lens blank grinding operation the switch will be shifted into its open position in order to stop the motor and resultantly stop drive of the spindle 8. The belt and pulley connection 21 is located in the open bottom compartment 15 and includes a pulley (not shown) on the lower end of the armature shaft of the motor 20, a pulley 22 on the lower end of the spindle 8 and an endless belt 23 around the two pulleys. Preferably the electric motor 20 is a constant speed motor and serves in connection with the belt and pulley connection 21 to drive the spindle 8 at a speed in excess of 1000 R. P. M. The spindle 8 has its upper end tapered upwards to a small degree, as shown in Figure 3, and embodies a centrally disposed longitudinally extending bore 24. The latter is preferably of uniform diameter from end to end and extends through the upper and lower end surface of the spindle. The lower end of the spindle is provided with an annular downwardly flared member 25. This member is located beneath the pulley 22 of the belt and pulley driving connection 21 and defines an internal upwardly tapered or frusto-conical socket 26, the upper end of which communicates with the lower end of the longitudinally extending bore 24 in the spindle 8.

The grinding wheel 9 serves in connection with use or operation of the apparatus to grind the lens blank 5 to the desired curvature and comprises a circular or disc-like body 27 and a hub 28. It is normally located within the central lower portion of the interior of the receptacle 7 and when in use is so positioned that the body 27 thereof extends horizontally. Preferably the body and hub of the wheel are formed integrally with one another. Brass, bronze or any other suitable metal is used to form the wheel and the latter is preferably in the form of a casting. The upper end surface of the body 27 of the grinding wheel is curved conformably to the curvature that is desired to be formed in the lens blank 5. If the lens blank is to be ground in a concave fashion the upper end surface of the wheel body 27 is convex as shown in the drawing. If the lens blank is to be ground so as to have a convex surface the working or upper end surface of the wheel body is made so that it is concavo or dished. Said upper end surface of the wheel body is cov-

ered with abrasive particles which are embedded in a matrix. Small or minute diamonds may be used as the abrasive particles. The matrix in which the particles are embedded may be formed of any suitable metal or other material and serves to bond the abrasive particles rigidly or fixedly to the upper end surface of the wheel body 27. If the grinding wheel is for rough grinding the lens blank 5 the abrasive particles are coarse, whereas if the wheel is to be used for an intermediate or so-called "finish" grinding operation the abrasive particles on the upper end surface of the body of the wheel are of fine mesh. The abrasive particles may extend throughout the entire area of the upper end surface of the outer body and are uniformly distributed throughout the matrix. The hub 28 of the grinding wheel is connected to, and depends from, the central portion of the circular or disc-like body 27. It embodies a central open bottom socket 29 which is shaped and adapted to receive the upper end of the spindle 8. As shown in Figure 3 the socket 29 is upwardly tapered in conformity with the upper end of the spindle in order that when the wheel is in place with respect to the spindle there is a friction drive between the two whereby the wheel is connected to the spindle for drive thereby. When it is desired to replace the grinding wheel 9 with another wheel having abrasive particles of different mesh than those on the upper end surface of the wheel 9 the wheel, as hereinafter described, is urged upwards by the device 11 in order to break the friction drive between the hub and the wheel and the upwardly tapered upper end of the spindle. The upper end portion of the hub 28 of the grinding wheel is solid in order to provide a closure member 30 at the upper or small end of the upwardly tapered socket 29.

The arm 10 overlies the receptacle 7 and normally extends substantially horizontally. One end of the arm is shaped to form a handle 31 and the other end is pivotally connected to a rotatable standard 32 in order that the arm is permitted to swing up and down and also laterally. A substantially vertical rod 33 extends through the central portion of the arm 10 and has a pointed lower end. The latter is adapted to fit within a socket in a holder 34 for the lens blank 5. After the lens blank to be ground is applied to the holder 34 it is placed against the abrasive covered upper end surface of the grinding wheel 9. Thereafter the lower end of the rod is inserted into the socket in the holder and the blank is urged downwards by applying downward pressure to it through the medium of the pressure arm 10. During a lens blank grinding operation the blank and holder spin about the rod and the lower surface of the blank is ground as the result of the abrasive action of the abrasive particles on the upper end surface of the wheel.

The device 11 has a twofold purpose in that it serves when actuated after a lens blank grinding operation to raise the grinding wheel 9 to a limited extent with respect to the spindle in order to break the friction drive between the wheel hub and the upper end of the spindle, and also to brake or stop the spindle. It is located for the most part beneath the base structure 6 of the grinding apparatus and comprises a bracket 35, a lever 36, a composite extensible shaft 37 and a rod 38. The bracket 35 is located under the table 12 and consists of a floor engaging bottom plate 39 and a pair of laterally spaced upstanding side plates 40. The bottom plate 39 of the bracket is shaped to fit flatly against the floor and em-

bodies holes 41 for lag screws 42. The latter serve fixedly to secure the bracket in place. The side plates 40 of the bracket are connected to, and project upwards from, the central portion of the bottom plate 39 and extend lengthwise of the table 12 on which the base structure 6 of the apparatus is positioned or mounted. As shown in Figure 1 the bracket 35 of the device 11 is disposed directly beneath the front portion of the base structure 6 and between the front legs of the table 12. The lever 36 is in the form of a bar and has the central portion thereof positioned between the upper marginal portions of the side plates of the bracket. A horizontal pivot pin 43 extends through aligned holes in the upper marginal portions of the bracket side plates and the central portion of the lever 36 and serves to support the lever so that it is free to swing in either direction in a vertical plane. The outer end of the lever 36 is provided with a foot pedal 44. When the foot pedal is depressed by the operator of the apparatus the lever 36 is caused to swing in a counterclockwise direction as viewed in Figure 1 of the drawings. The rear end of the lever 36 is provided with a depending stop screw 45 for limiting clockwise swinging movement of the lever. The shank of the stop screw extends into an internally threaded socket in the rear end of the lever 36 and embodies a lock nut 46 for securing it in place. The head of the stop screw is adapted to abut against the floor when the lever 36 is swung to its fullest extent in a clockwise direction. By adjusting the stop screw 45 inwards or outwards with respect to the rear end of the lever 36 the extent of clockwise swinging of the lever 36 may be regulated or adjusted. A leaf spring 47 urges the lever 36 to swing in a clockwise direction as viewed in Figure 1. One end of this spring bears against the portion of the lever 36 that is directly inwards of the foot pedal 44 and the other end of the spring is disposed between the side plates 40 of the bracket 35, and is operatively connected to a pair of bolts 48. When the outer end of the lever 36 is swung downwards the free end of the leaf spring 47 swings downwards and when the outer end of the lever is released such free end of the leaf spring springs upwards and serves to shift upwards or retract the outer end of the lever. The extensible composite rod 37 is located above, and projects upwards from, the rear end of the lever 36 and comprises a tubular lower section 49 and a solid upper section 50. The lower end of the tubular lower section 49 is bifurcated. It straddles the rear end of the lever 36 and is pivotally connected thereto by way of a horizontal pivot pin 51. When the lever 36 is swung in a counterclockwise direction as the result of the operator depressing the foot pedal 44 the upstanding composite shaft 37 is shifted upwards and when the lever is swung in a clockwise direction by the spring 47 in connection with release of the foot pedal 44 the shaft 37 is shifted downwards. The lower end of the upper shaft section 50 fits slidably within the upper end of the lower shaft section 49 and is releasably held in place by means of a set screw 52. The latter extend transversely through the upper end of the tubular lower shaft section 49 and when tightened locks the upper shaft section against sliding movement with respect to the lower shaft section. When the set screw is released the upper shaft section may be slid upwards or downwards with respect to the tubular lower section in order to adjust the over-all length of the upstanding shaft 37. The upper end of

the solid upper shaft section 50 is aligned with a hole 53 in the top of the table 12 and embodies a frusto-conical brake member 54. The latter is upwardly tapered in conformity with the upwardly tapered socket 26 in the annular downwardly flared member 25 in the lower end of the spindle 8 and coacts with said member to form a brake for effecting stoppage of the spindle at the conclusion of the lens blank grinding operation and after opening of the switch for the electric motor 20. When the lever 36 is swung in a counterclockwise direction as the result of the operator depressing the foot pedal 44 the composite shaft 37 shifts upwards, as heretofore pointed out, with the result that the frusto-conical brake member on the upper end of the solid upper shaft section 50 moves into engagement with the annular downwardly flared member 25 and coacts therewith to brake or stop the spindle 8. The members 25 and 54 serve not only as a medium or instrumentality for braking or stopping the spindle 8 at the conclusion of a lens blank grinding operation but also to limit counterclockwise swinging of the lever 36. The rod 38 of the device 11 extends vertically and is located for the most part above the solid upper section 50 of the upstanding shaft 37. The lower end of the rod embodies an external screw thread 55 and fits within an internally threaded longitudinally extending bore 56 in the upper end of the upper shaft section 50. A lock nut 57 is mounted on the screw threaded lower end of the rod 38 and serves when tightened to lock the rod against longitudinal or axial displacement with respect to the shaft section 50. When the lock nut is loosened the rod may be longitudinally adjusted with respect to the shaft section 50 by turning it in one direction or the other. The upper portion of the rod 38 extends slidably through the longitudinal bore 24 in the spindle 8, as best shown in Figure 3. The rod 38 is so adjusted so far as its operative length is concerned that when the shaft 37 is shifted upwards to its fullest extent in connection with counterclockwise swinging of the lever 36 the upper end of the rod is brought into abutment with the closure member 30 for the upper end of the socket 29 in the hub 28 of the grinding wheel 9 and effects such raising of the wheel with respect to the upper end of the spindle as to break the friction drive between the grinding wheel hub and the upwardly tapered end of the spindle. It is contemplated that the rod 38 will be so adjusted with respect to the solid upper shaft section 50 that when the composite shaft is shifted upwards to its fullest extent at the conclusion of a lens blank grinding operation the rod 38 will only raise the grinding wheel but a small distance with respect to the spindle in order to preclude the wheel from falling away from the upper spindle and onto the bottom wall of the receptacle 7. The screw thread connection between the lower end of the rod and the upper end of the upper shaft section 50 permits the rod to be longitudinally adjusted with respect to said shaft section and hence provides an adjustment whereby the amount of upward displacement of the grinding wheel with respect to the spindle in connection with upward shift of the composite shaft 37 may be controlled or regulated.

In using the apparatus to grind the eyeglass lens blank 5 the apparatus is supported by closing the switch for the electric motor 20. Closing of such switch results in conjoint drive of the spindle 8 and the grinding wheel 9. After starting of the motor the blank 5 is pressed against the upper

end surface of the grinding wheel by applying downward pressure on the arm 10. After the blank is ground to the desired extent the switch for the motor is opened and the foot pedal 54 is depressed so as to effect upward shift of the composite shaft 37. In connection with upward shift of such shaft the frusto-conical brake member 54 is brought into engagement with the inner periphery of the annular downwardly flared coacting brake member 25 on the lower end of the spindle 8 and coacts therewith to effect braking or stoppage of the spindle and concurrently the rod is shifted upwards and effects limited upward displacement of the grinding wheel with respect to the upper end of the spindle 8. As soon as the grinding wheel is shifted upwards or raised by the rod it is removed and another grinding wheel is substituted for it in order to adapt the apparatus to perform another lens blank grinding operation. Prior to application of the other grinding wheel to the upper end of the spindle the lever 36 is released in order that the leaf spring 47 is permitted to retract the lever, i. e., swing the lever in a clockwise direction as viewed in Figure 1. Such swinging movement on the part of the lever results in downward shift of the composite shaft 37 and resultant disengagement of the brake member 54 from the coacting brake member 25 and lowering of the rod 38.

The herein described eyeglass lens grinding apparatus may be operated expeditiously and with facility due to the fact that it includes the device 11 which when actuated at the conclusion of a lens blank grinding operation serves conjointly to brake or stop the spindle 8 and shift upwards the grinding wheel in order to break the friction drive between it and the upper end of the spindle.

The invention is not to be understood as restricted to the details set forth since these may be modified within the scope of the appended claims without departing from the spirit and scope of the invention.

Having thus described the invention what we claim as new and desire to secure by Letters Patent is:

1. In a lens grinding apparatus of the type that comprises an upstanding rotatably mounted spindle with driving means therefor, and a horizontal grinding wheel having a hub part shaped to slide into interfitting relation with the upper end of the spindle when the wheel is shifted downwards toward the spindle and adapted when in such relation to connect the wheel for frictional drive by said spindle, a device designed for use in disconnecting the wheel from the spindle after a lens grinding operation and embodying a lever located beneath the spindle and mounted and arranged so as to swing to a limited extent back and forth in a vertical plane, and an elongated upstanding member having the lower end thereof pivotally connected to the lever and its upper end disposed adjacent the spindle, adapted when the lever is swung to its fullest extent in one direction to raise the wheel to a small extent with respect to the spindle and effect breaking of the frictional drive between the wheel hub part and the spindle, and comprising a pair of telescopically arranged sections connected together so that they are adjustable longitudinally one relative to the other in order to vary the operative length of the member.

2. A lens grinding apparatus comprising a vertically extending rotatably mounted spindle provided with driving means therefor and having a bore extending longitudinally therethrough, a

horizontal grinding wheel having a depending hub part shaped to slide into interfitting relation with the upper end of the spindle when the wheel is shifted downwards towards the spindle and adapted when in such relation to connect the wheel for frictional drive by said spindle, and a device designed for use in disconnecting the wheel from the spindle after a lens grinding operation and embodying a lever located beneath the spindle and mounted to swing in a vertical plane, an upstanding shaft positioned beneath, and in alignment with, the spindle, having the lower end thereof pivotally connected to the lever, and adapted when the lever is swung in one direction to move upwards into a position wherein the upper end thereof is in abutment with the lower end of the spindle, and a vertically extending rod extending longitudinally through the bore in the spindle, having the lower end thereof connected to the upper end of the shaft, and adapted when the shaft is shifted upwards in response to swinging of the lever in said one direction to raise the wheel to a slight extent with respect to the spindle and effect breaking of the frictional drive between said hub part and said upper end of the spindle.

3. A lens grinding apparatus comprising a vertically extending rotatably mounted spindle provided with driving means therefor and having a bore extending longitudinally therethrough, a horizontal grinding wheel having a depending hub part shaped to slide into interfitting relation with the upper end of the spindle when the wheel is shifted downwards towards the spindle and adapted when in such relation to connect the wheel for frictional drive by said spindle, and a device designed for use in disconnecting the wheel from the spindle after a lens grinding operation and embodying a lever located beneath the spindle and mounted to swing in a vertical plane, an upstanding shaft positioned beneath, and in alignment with, the spindle, having the lower end thereof pivotally connected to the lever, and adapted when the lever is swung in one direction to move upwards into a position wherein the upper end thereof is in abutment with the lower end of the spindle, and a vertically extending rod extending longitudinally through the bore in the spindle, having the lower end thereof connected to the upper end of the shaft so that it is longitudinally adjustable with respect to said shaft, and adapted when the shaft is shifted upwards in response to swinging of the lever in said one direction to raise the wheel to a slight extent with respect to the spindle and effect breaking of the frictional drive between said hub part and said upper end of the spindle.

4. A lens grinding apparatus comprising a vertically extending rotatably mounted spindle provided with driving means therefor and having a bore extending longitudinally therethrough, a horizontal grinding wheel having a depending hub part shaped to slide into interfitting relation with the upper end of the spindle when the wheel is shifted downwards towards the spindle and adapted when in such relation to connect the wheel for frictional drive by said spindle, and a device designed for use in disconnecting the wheel from the spindle after a lens grinding operation and embodying a lever located beneath the spindle and mounted to swing in a vertical plane, an upstanding shaft positioned beneath, and in alignment with the spindle, having the lower end thereof pivotally connected to the lever, adapted when the lever is swung in one direction to move upwards into a position wherein the upper end thereof is in abutment with the lower end of the

spindle, and consisting of upper and lower telescopic and adjustably connected shaft sections, and a vertical rod extending longitudinally in the bore in the spindle, having the lower end thereof connected to the upper end of the shaft so that it is longitudinally adjustable with respect to said shaft, and adapted when the shaft is shifted upwards in response to swinging of the lever in said one direction to raise the wheel to a slight extent with respect to the spindle and effect breaking of the frictional drive between said hub part and said upper end of the spindle.

5. A lens grinding apparatus comprising a vertically extending rotatably mounted spindle provided with driving means therefor and having a bore extending longitudinally therethrough, a horizontal grinding wheel having a depending hub part shaped to slide into interfitting relation with the upper end of the spindle when the wheel is shifted downwards towards the spindle and adapted when in such relation to connect the wheel for frictional drive by said spindle, and a device designed for use in disconnecting the wheel from the spindle after a lens grinding operation and embodying a lever located beneath the spindle and mounted to swing in a vertical plane, an upstanding shaft positioned beneath, and in alignment with, the spindle, having the lower end thereof pivotally connected to the lever, and adapted when the lever is swung in one direction to move upwards into a position wherein the upper end thereof is in abutment with the lower end of the spindle, a vertically extending rod extending longitudinally through the bore in the spindle, having the lower end thereof connected to the upper end of the shaft, and adapted when the shaft is shifted upwards in response to swinging of the lever in said one direction to raise the wheel to a slight extent with respect to the spindle and effect breaking of the frictional drive between said hub part and said upper end of the spindle, and a spring applied to the lever so that it serves to urge the lever to swing in the opposite direction in order to retract the shaft and rod.

6. In a lens grinding apparatus of the type that comprises a rotatably mounted spindle with driving means therefor, and a grinding wheel having a hub part shaped to slide into interfitting relation with the spindle when the wheel is shifted towards the spindle and adapted when in such relation to connect the wheel for frictional drive by said spindle, the combination of a movably mounted member, means operative automatically in response to movement of the member in one direction to brake the spindle, and means operative automatically in response to shift of the member in said one direction to shift the wheel away from the spindle for removal purpose and effect breaking of the frictional drive between the hub part and the spindle.

7. In a lens grinding apparatus of the type that comprises a rotatably mounted spindle with driving means therefor, and a grinding wheel having a hub part shaped to slide into interfitting relation with the spindle when the wheel is shifted towards the spindle and adapted when in such relation to connect the wheel for frictional drive by said spindle, the combination of a member mounted so that it is shiftable bodily back and forth, brake means operative automatically in response to shift of the member in one direction to arrest drive of the spindle and means connected to the member and operative automatically in response to shift of said member in said one direction to shift the wheel away from the spindle

for wheel removing purposes and effect breaking of the frictional drive between the hub part and said spindle.

8. In a lens grinding apparatus of the type that comprises a rotatably mounted spindle with driving means therefor, and a grinding wheel having a hub part shaped to slide into interfitting relation with the spindle when the wheel is shifted towards the spindle and adapted when in such relation to connect the wheel for frictional drive by said spindle, the combination of a member mounted so that it is shiftable bodily back and forth, brake means operative automatically in response to shift of the member in one direction to arrest drive of the spindle, means connected to the member and operative automatically in response to shift of said member in said one direction to shift the wheel away from the spindle for wheel removing purposes and effect breaking of the frictional drive between the hub part and said spindle, and spring means applied to the member so that it urges the latter in the opposite direction.

9. A lens grinding apparatus comprising in combination a vertically extending rotatably mounted spindle provided with means for driving it and embodying at its lower end a brake member, a horizontal grinding wheel having a depending hub part shaped to slide into interfitting relation with the upper end of the spindle when the wheel is shifted downwards towards the spindle and adapted when in such relation to connect the wheel for frictional drive by said spindle, a lever located beneath the spindle and mounted to swing in a vertical plane, an upstanding shaft positioned beneath, and in alignment with, the spindle, having the lower end thereof connected to the lever and its upper end provided with a coacting brake member, and adapted when the lever is swung in one direction to move upwards into a position wherein the coacting brake member at its upper end is in abutment with the first mentioned brake member and the two members serve to arrest drive of the spindle, and a member connected to the upper end of the shaft and adapted in connection with upward movement of the shaft to raise the wheel to a slight extent with respect to the spindle and effect breaking of the frictional drive between the wheel hub part and said upper end of the spindle.

10. A lens grinding apparatus comprising, in combination a vertically extending rotatably mounted spindle provided with means for driving it and embodying at its lower end a brake member, a horizontal grinding wheel having a depending hub part shaped to slide into interfitting relation with the upper end of the spindle when the wheel is shifted downwards towards the spindle and adapted when in such relation to connect the wheel for frictional drive by said spindle, a lever located beneath the spindle and mounted to swing in a vertical plane, an upstanding shaft positioned beneath, and in alignment with, the spindle, having the lower end

thereof connected to the lever and its upper end provided with a coacting brake member, and adapted when the lever is swung in one direction to move upwards into a position wherein the coacting brake member at its upper end is in abutment with the first mentioned brake member, and the two members serve to arrest drive of the spindle, a member connected to the upper end of the shaft and adapted in connection with upward movement of the shaft to raise the wheel to a slight extent with respect to the spindle and effect breaking of the frictional drive between the wheel hub part and said upper end of the spindle, and spring means applied to the lever so that it serves to urge the latter to swing in the opposite direction.

11. A lens grinding apparatus comprising a vertically extending rotatably mounted spindle provided with drive means thereof, having a bore extending longitudinally therethrough and embodying at its lower end a brake member, a horizontal grinding wheel having a depending hub part shaped to slide into interfitting relation with the upper end of the spindle when the wheel is shifted downwards towards the spindle and adapted when in such relation to connect the wheel for frictional drive by said spindle, a lever located beneath the spindle and mounted to swing in a vertical plane, an upstanding shaft positioned beneath, and in alignment with, the spindle, having the lower end thereof pivotally connected to the lever and its upper end provided with a coacting brake member, and adapted when the lever is swung in one direction to move upwards into a position wherein its coacting brake member is in engagement with the first mentioned brake member and the two brake members serve to arrest drive of the spindle, and a vertical rod extending longitudinally through the bore in the spindle, having the lower end thereof connected to the upper end of the shaft, and adapted when the shaft is moved upwards into the aforementioned position to raise the wheel to a slight extent with respect to the spindle and effect breaking of the frictional drive between the wheel hub part and said upper end of the spindle.
